REED FACER

Walter S. Browder, 125 Dallas Ave.,
Weatherford, Tex. 76086
Filed Sept. 26, 1966, Ser. No. 582,062
2 Claims. (Cl. 84—458)

This invention relates to a reed facer, and it concerns more particularly a small planing or scraping device, readily adapted to be carried in the pocket or in the instrument case, for facing, and for refacing as necessary, the reeds of musical reed instruments, such as clarinets and saxophones, to provide a perfectly smooth, planar surface on one side of the reed.

Reeds as employed in musical reed instruments, such as clarinets and saxophones, ordinarily have initially a smooth, planar surface on one side thereof for opposing engagement with the mouthpiece of the instrument. But the reeds are affected by their environment, including the temperature and humidity of the atmosphere, and in time they tend to warp, so that they are no longer true and do not function well in use, and it may be necessary to discard them. In practice a musician may discard a number of reeds before selecting for use one that is in relatively good condition.

The performance of a musical reed instrument necessarily depends largely on the condition of the reed, and an object of the invention is to provide a reed facer as described for convenience in maintaining the reed in condition for use at all times.

By use of the reed facer of the invention the reed may be caused to remain serviceable, in condition for use, for an indefinite period of time, so that a single reed may be sufficient and it is not necessary to replace the reed frequently or to provide any great number of them to select from. At the same time the performance of the musical instrument on which the reed is used remains constant and true, and the instrument is responsive to the skill of the musician.

The invention will be readily understood by referring to the following description and the accompanying drawing, in which:

FIG. 1 is a full size, top plan view of a reed facer embodying the invention, showing a reed arranged thereon as in facing or refacing the reed by advancing it longitudinally of the device, across the exposed edge of the upwardly facing blade positioned intermediate its ends;

FIG. 2 is a side elevational view of the reed facer;

FIG. 3 is a bottom plan view thereof; and

FIG. 4 is a view showing one side of the blade and its holder in a detached position thereof.

Referring to FIG. 1 of the drawing, the numeral 1 designates generally a reed facer embodying the invention, and the numeral 2 indicates generally a reed for a musical reed instrument, such as a clarinet or a saxophone.

As shown, the reed 2 is arranged on the reed facer 1 as in facing or refacing the reed 2 by advancing the reed 2 longitudinally relative to the reed facer 1, in sliding engagement therewith, while supporting the reed facer 1 in fixed position on a supporting surface (not shown).

The reed facer 1 includes an elongated body 3 which is generally rectangular and of hollow, molded construction, and advantageously may be formed of light weight metal or plastic material.

The body 3, which in use is disposed horizontally, as shown, and has a width greater than its height, has a planar top surface 4 and is open on its under side. A transverse partition 5 extends between the two opposite sides thereof, indicated by the numerals 6, 7, intermediate its ends 8, 9.

2

The body 3 has a transverse slot 10 intermediate its ends, extending downwardly from the top surface 4 and bisecting the upper portion of the transverse partition 5. The slot 10, which has a depth approaching one-half the height of the body 3, extends through the two opposite sides 6, 7 and is open at its ends.

A blade 11, shown in FIG. 4, is received bodily in the slot 10 and has its cutting edge, indicated by the numeral 12, facing upwardly and extending slightly above the top surface 4 whereby it is exposed. The blade 11 is adjustably positioned in the slot 10 whereby it may be raised and lowered, and is secured against displacement therefrom as hereinafter described.

The blade 11, two of which advantageously may be formed by dividing a conventional double edge safety razor blade along its longitudinal center line, has a backing strip or holder 13, channel shaped in transverse section, embracing the longitudinal edge thereof opposite its cutting edge 12, which is positioned lowermost, adjacent the bottom of the slot 10. A pair of ears 14, which comprise reduced end portions of the blade 11, extend outwardly beyond the ends of the slot 10 for use as hereinafter described.

A pair of spring biased levers 15 on opposite sides of the body 3 each have one of its end portions engageable over one of the ears 14 whereby the blade 11 is secured against displacement from the slot 10.

The levers 15 are passed through transverse openings therefor in the adjacent ends of a pair of rotatable shafts 16, which are passed through the respective sides 6, 7 and are acted on, respectively, by a pair of coil springs 17.

Each of the springs 17 surrounds the corresponding shaft 16 and is connected thereto at one of its ends, and has its opposite end connected to the transverse partition 5, whereby the levers 15 are biased rotatively about their respective axes, to thereby yieldably urge the blade 11 against displacement from the bottom of the slot 10.

The levers 15 have small knobs 18 on one of their ends for engagement by the fingers, and the arrangement is such that the blade 11 may be removed from the slot 10 upon rotating the levers 15 about the shafts 16 against the resistance of the springs 17.

A pair of stops 19 on the sides 6, 7 are engageable by the respective levers 15 to limit pivotal movement thereof in one direction only, to prevent the springs 17 from unwinding completely upon removal of the blade 11 from the slot 10.

A pair of adjusting screws 20, which are arranged longitudinally of the body 3 in laterally spaced relation thereto, are threaded, as at 21, for engagement with correspondingly threaded openings therefor in the end 9 of the body 3.

The adjusting screws 20 are pointed at their inner ends, as at 22, which are passed through openings therefor in the transverse partition 5 communicating with the slot 10 and are engageable under opposite end portions of the blade 11 and its holder 13, between the holder 13 and the bottom of the slot 10, to thereby level the blade 11 and to adjust it vertically relative to the slot 10 to control the depth of cut.

A locking screw 23, which is arranged longitudinally of the body 3 along its longitudinal center line, is threaded, as at 24, for engagement with a correspondingly threaded opening therefor in the end 8 of the body 3.

The locking screw 23 is blunt at its inner end, as at 25, which is passed through an opening therefor in the transverse partition 5 communicating with the slot 10 for abutting, clamping engagement with the adjacent side of the blade 11 and its holder 13, to positively secure the blade 11 in any of its adjusted positions.

The invention may be modified in various ways without departing from the spirit and scope thereof.

I claim:

1. In a planing device for facing and refacing the reeds of musical reed instruments, the combination of an elongated rectangular body of molded, hollow construction characterized by its small size and its light weight, and having a length not substantially greater than twice the length of a reed, adapted to be arranged horizontally on a supporting surface in its operative position, the body having a planar top surface and being open on its under side, and having a transverse partition extending between its two opposite sides, intermediate its ends, and having a transverse slot intermediate its ends extending downwardly from its top surface, a razor type blade received bodily in the slot with its cutting edge facing upwardly and extending slightly above the top surface, and with the ends of the blade extending laterally outwardly beyond the sides of the body, a pair of adjusting screws arranged longitudinally of the body, on one side of the transverse partition, threadedly engaging openings therefor in the adjacent end of the body and having pointed inner ends received in openings therefor in the transverse partition communicating with the slot and engageable under op-

posite end portions of the blade, between the blade and the bottom of the slot, and a locking screw arranged longitudinally of the body, on the side of the transverse partition opposite the adjusting screws, threadedly engaging an opening therefor in the corresponding end of the body and having a blunt inner end received in an opening therefor in the transverse partition communicating with the slot for abutting, clamping engagement with the adjacent side of the blade.

2. The structure of claim 1, and a pair of spring biased levers on opposite sides of the body, each adjustable pivotally about an axis parallel to the plane of the blade, engageable over adjacent end portions of the blade, exteriorly of the body, to secure the blade against displacement from the slot.
